STEAM BOARD

Filed Feb. 6, 1928

Inventor:
Herman Betke.

By *Herman Betke*.

Attorney.

UNITED STATES PATENT OFFICE

HERMAN BETKE, OF DENVER, COLORADO

STEAM BOARD

Application filed February 6, 1928. Serial No. 252,215.

An object of this invention is to provide an improved construction for a fabric-steaming apparatus or steam board.

A further object of the invention is to provide an improved construction for a steam board adapted for use in the steaming of relatively small fabric tubes such as neckties and the like.

A further object of the invention is to provide an improved construction for a steam board having in combination a plurality of hot bucks adapted for use in the steaming of relatively small fabric tubes and a hot plate or puff-iron whereon said fabric tubes may be dried and ironed.

A further object of the invention is to provide an improved construction for a steam board wherein a plurality of bucks and a puff-iron are heated and maintained at high temperature by steam from a common source.

A further object of the invention is to provide an improved construction for a steam board wherein a plurality of bucks and a puff-iron are heated and maintained at high temperature by means of continuous circulation of steam from a common source therethrough, provision being made for by-passing some of said steam, when desired, through the steaming compartments of said bucks.

A further object of the invention is to be found in the provision of a steaming buck adapted for use in the steaming of small fabric tubes, said buck comprising a heating and a steaming compartment, both of said compartments being operatively connected with a common source of steam.

My invention consists in the construction, arrangement and combination of elements hereinafter set forth, pointed out in the claims and illustrated by the accompanying drawing, in which

Figure 1 is an elevation of the improved apparatus, completely assembled and in position for practical use. Figure 2 is a side elevation of the apparatus at right angles to the showing of Figure 1. Figure 3 is a vertical section through one of the bucks on the indicated line 3—3 of Figure 1. Figure 4 is a cross section through one of the bucks taken

at right angles to the showing of Figure 3 and on the indicated line 4—4 of Figure 1.

In the construction of the improvement as shown, a stand or pedestal 10 is provided with a base 11 adapted to be secured to a floor or other suitable support, said stand 10 being of any desired length, size and shape and provided with oppositely-extending arms 12

secured adjacent its upper end and serving as convenient supports to receive and hold articles to be treated on the apparatus. The upper end of the stand 10 is secured to and supports a hollow, cylindrical member 13 with its axis at right angles to that of the stand 10, and diverging tubular arms lead

upwardly and outwardly from either end of the member 13. Since the tubular arms are identical in construction and function, one only will be described. Each of the diverging arms comprises pipe sections 14 and suitable fittings connecting the member 13, through T 15 and 16, with a boss 17 formed on and extending from the base of a steam buck 18, said buck having a substantially oval base and side walls tapering inwardly

therefrom to form a shell having the appearance of a flattened cone, the interior of said shell communicating through a bore in the boss 17 with the pipe sections 14. The pipe section 14 connecting the T 15 and 16 is

reduced in diameter within the T 16 to form an elongated nozzle 19, said nozzle extending axially of the T 16, boss 17 and pipe connections therebetween to and within the shell of the buck 18 and as near to the apex of said shell as is convenient. A steam line 20 leads

from any suitable source of steam through a cut-off valve 21 to the member 13, from whence the diverging arms offer passage to the steam through the pipe connections 14, T 15 and nozzle 19 to the interior of the shells of the bucks 18, return of the steam being

had around said nozzle 19 through the boss 17, upper pipe connection 14 and T 16 to a return steam line 22 suitably branched and connected with the outlets of the T 16. Thus provision made, when the valve 21 is open, for continuous circulation of steam through and within the bucks 18, whereby said bucks are heated and maintained at high tempera-

ture and in condition for successful operation of the steaming devices. Each of the bucks 18 is provided with a face plate 23 overlying the flattened surface of said buck and marginally secured thereto in any suitable manner. The face plates 23 are curved and tapered to conform to the contours of the bucks and are perforated to afford communication from the chamber between said buck and face plate to the atmosphere. A branch steam line 24 is led from each of the T 15 through a manually-operable valve 25 to discharge through the base of the buck 18 within the chamber between said buck and its face plate 23, and a drain pipe 26 is threaded into the lowermost corner of the steaming chamber of each of the bucks 18 to provide for the escape of any water of condensation that might collect therein. A hot plate or puff-iron 30, of common design and function, is supported on a steam branch 27 connecting the interior of said puff-iron with the member 13 through a manually-operable valve 28, and a return steam branch 29 connects said puff-iron with the steam return line 22, so that, when the valve 28 is open, steam may circulate freely within said puff-iron and heat the same.

In the operation of the apparatus, the steam line 20 and steam return line 22 being properly connected with a source of steam, the valve 21 is opened and steam is permitted to circulate through the bucks 18 continuously, heating said bucks, the valves 25 and 28 being closed. Fabric tubes, such as neckties or the like, are slipped over the bucks 18 and face plates 23, the valve 25 is opened, and steam is discharged through the perforations of the face plate 23, thoroughly steaming and renovating the fabric thereon, the high temperature of the bucks 18 preventing forming of water through condensation and insuring dry, hot steam for the renovating process. The valve 28 may be opened at any time to permit steam to circulate within and heat the puff-iron 30, so that when the fabric is removed from the buck 18 it may be folded or creased and drawn across said puff-iron, which latter operation thoroughly dries and irons the fabric so treated.

The bucks 18 are preferably of different sizes and a number of such bucks may be provided for each apparatus, the construction and operation of each being as above described.

It is obvious that the face plates 23 may be formed integral with the bucks 18 if desired, and that many other changes or modifications of construction, form and relation of elements may be had without departing from the spirit of my invention, which is to be understood as being defined and limited solely by the scope of the appended claims.

I claim as my invention—

1. In an apparatus of the character described having a support, a tubular arm rising from said support and a steam line communicating with the bore in said arm, a buck on the outer end of said arm, said buck having a perforate and an imperforate compartment and ports opening through the base of said compartments, the port of said imperforate compartment registering with the bore of said arm and the port of the perforate compartment registering with a branch steam line leading from said arm through a manually-operable valve, together with a nozzle of reduced diameter within the bore of said arm, interrupting said bore and extending within and adjacent the outer end of said imperforate compartment and a steam passage between the outer wall of said nozzle and the inner wall of said bore and a steam return line communicating with said passage. 70 75 80 85

2. In an apparatus of the character described having a support, a tubular arm rising from said support, a steam line communicating with the bore in said arm, a buck having a perforate and an imperforate compartment fixed to the outer end of said arm with said imperforate compartment communicating with the bore of said arm, means whereby steam may be caused to circulate continuously within said imperforate compartment and selectively through said perforate compartment, said means comprising a nozzle of reduced diameter within the bore of said arm, interrupting said bore and extending within and adjacent the outer end of said imperforate compartment, a steam passage between the outer wall of said nozzle and the inner wall of said bore, a steam return line communicating with said passage and a branch steam line leading through a manually-operable valve to connect the port of said perforate compartment with the bore of said arm between said nozzle and steam line, together with a drain tube for said perforate compartment. 90 95 100 105 110

3. In an apparatus of the character described, a support, a hollow arm rising from said support, a hollow buck closing the end of said arm and communicating with the interior thereof, a steam line communicating with the interior of said arm, a nozzle of reduced diameter within said arm and buck and extending adjacent the outer end of said buck, the base of said nozzle completely filling the bore within said arm between said steam line and buck, a passage defined by the inner wall of said arm and the outer surface of said nozzle between said buck and the base of said nozzle and a return steam line communicating with said passage; together with a perforate steaming chamber carried by said buck and a valved steam line operatively connecting said chamber with said arm between said support and said nozzle. 115 120 125 130

4. In an apparatus of the character described, a support, a hollow arm rising from said support, a hollow buck closing the end of said arm and communicating with the interior thereof, a perforate chamber on and sealed from one face of said buck, a steam line communicating with the interior of said arm, a valve-controlled branch of said steam line communicating with the interior of said perforate chamber whereby steam may be 10 optionally circulated within and through said chamber, a nozzle of reduced diameter within said arm and buck and extending adjacent the outer end of said buck, the base of said nozzle completely filling the bore within said arm between said steam line and buck, a passage defined by the inner wall of said arm and the outer surface of said nozzle between said buck and the base of said nozzle 15 and a steam return line communicating with said passage, whereby steam may be continuously circulated within said buck to heat said buck and chamber.

Signed at Denver, in the county of Denver and State of Colorado, this 9th day of 25 December, 1927.

HERMAN BETKE.
